US00D880592S

(12) **United States Design Patent** (10) Patent No.: **US D880,592 S**
 Lee et al. (45) Date of Patent: ** Apr. 7, 2020

(54) **DIGITAL SIGNAGE**

- (71) Applicant: **LG ELECTRONICS INC.**, Seoul (KR)
- (72) Inventors: **Yoonkyeong Lee**, Seoul (KR); **Yongho Lee**, Seoul (KR); **Jaewon Lim**, Seoul (KR)
- (73) Assignee: **LG ELECTRONICS INC.**, Seoul (KR)
- (**) Term: **15 Years**
- (21) Appl. No.: **35/505,952**
- (22) Filed: **Apr. 27, 2018**

(80) **Hague Agreement Data**

- Int. Filing Date: **Apr. 27, 2018**
 Int. Reg. No.: **DM/100973**
 Int. Reg. Date: **Apr. 27, 2018**
 Int. Reg. Pub. Date: **Nov. 2, 2018**

(30) **Foreign Application Priority Data**

- Oct. 27, 2017 (KR) 30-2017-0050046
